CLAIM

The ornamental design for a handheld light, as shown and described.

DESCRIPTION

FIG. 1 is a right side perspective view of a handheld light; FIG. 2 is a right side elevation view thereof; FIG. 3 is a left side elevation view thereof; FIG. 4 is a front elevation view thereof; FIG. 5 is a rear elevation view thereof; FIG. 6 is a top plan view thereof; and, FIG. 7 is a bottom plan view thereof. The broken lines show portions of the handheld light which form no part of the claimed design.
